Inventor

UNITED STATES PATENT OFFICE.

ALLEN R. DAYMON, OF PETERS CREEK, ILLINOIS.

TRACE-CARRIER.

SPECIFICATION forming part of Letters Patent No. 626,982, dated June 13, 1899.

Application filed May 17, 1898. Serial No. 680,929. (No model.)

To all whom it may concern:

Be it known that I, ALLEN R. DAYMON, a citizen of the United States, residing at Peters Creek, in the county of Hardin and State 5 of Illinois, have invented certain new and useful Improvements in Securing Devices for Snap-Buckles; and I do hereby declare the following to be a full, clear, and exact description of the invention, such as will enable others skilled in the art to which it appertains 10 to make and use the same.

My invention relates to certain new and useful improvements in harness attachments; and it consists of what might be termed a 15 "securing device" or "snap-buckle," the object being to provide reliably efficient means for holding the trace-chain or tug in the desired position, whereby it may be readily secured and disengaged.

As will be seen from the following specification and the accompanying drawings, my invention consists in certain novel construction and arrangement of parts, which will be clearly pointed out in the claims appended.

In the accompanying drawings, Figure 1 is a perspective view of my securing device or snap complete. Fig. 2 is a plan view thereof on a slightly-enlarged scale from that shown in Fig. 1. Fig. 3 is a central section of Fig. 30 2 on line α α . Fig. 4 is a detail plan view of the locking-tongue removed from the frame.

Briefly stated, my invention consists in a suitable frame or body having an overlapping end designed to form a seat and 35 for receiving the tug or trace-chain, and a coöperative spring-latch designed to lock the trace in an adjusted position within said seat and permit the same to be readily removed.

Referring in detail to the several parts of 40 my invention, 1 represents the upper end of my improved snap-buckle, from which extend the parallel sections 2, the inwardly-inclined sections 3, and the hook portions or members 4, all of said parts being preferably 45 cast integrally of any suitable material. I also secure upon the outer side of the sections 2 by casting the same integrally or otherwise attaching thereto the bracket 5, which preferably extends upward slightly above the plane 50 of said sections, to which I secure in any preferred way, as by rivets 6, the spring-controller 7, which, it will be seen, is bifurcated at its up-

per end and united at its lower end 8, the latter being preferably connected, as by rivets 9, to the hook-closing member 10. In order 55 that the hook-closing member 10 may be snugly seated and included within the hook-section, I prefer to cut away the central portion of said section, and within such opening I dispose the member 10, so that its outer 60 surface will lie flush with the hook member, and, further, in order that said member may be more securely held in its operative position without unduly taxing the capacity of the spring 7 I prefer to provide said member with 65 the recess 11, which is designed to receive the transverse rib 12, formed upon the cross-bar 13, which, in connection with the end bar 14, will prevent an undue upward extension of the member 10, as will be readily apparent 70 from Fig. 3 of the drawings.

In order that the member 10 and its coöperating spring 7 may be readily controlled, I provide the thumb-piece 15, which when pressed upon will bring the lower end of the 75 spring downward sufficiently to force the upper surface of the bar 13 on a line with the upper surface of the lower part of the hook portions or members 4, when the trace-chain 16 may be readily inserted within the seat provided by hook member or removed therefrom.

My improved securing device is designed to be secured in any preferred way to the back-band of harness, so that the same will rest upon either side of the animal at a point 85 which will enable the hook portions or members 4 to readily receive a link of the trace-chain at this point, and thus hold said chain against undue upward or downward displacement.

It will of course be readily apparent that the spring 7 and the member 10 may be formed in one piece, in which case material of sufficient resiliency should be selected, which will enable the rivets 9 to be entirely dispensed 95 with.

In Fig. 1 I have shown, as indicated at 17, that my improved securing snap or buckle may be readily attached to the back-band by stitching said portion or otherwise securing 100 the same directly to the band at a point which will leave the securing device in the desired position.

While I have described the preferred con-

struction to be employed in producing and assembling the several coöperating parts of my securing device, it will be understood that any substantial equivalent of the construction and arrangement described is comprehended by me, and I do not therefore wish to be confined strictly to the exact showing I have made.

It will be readily apparent that by cutting

- 10 away the central portion of the hook member a more graceful outline is produced, resulting in greater lightness without impairing the strength of the several parts, the transverse sections 13, 14, and 18 being designed to provide the requisite reinforcement at the points where the same are located.

By providing a proper finish to the several parts my improved securing device will add an attractive finish to the harness, and since

- 20 the several features are very simple in construction the entire device may be produced at a minimum cost, and at the same time it will prove of permanent character and reliable efficiency.

- 25 25 What I claim as new, and desire to secure by Letters Patent, is—

1. The herein-described securing device for trace-chains or the like, consisting of the end section 1, the inwardly-inclined side sections

- 30 3 and the hook extensions or members 4, integral with said parts, said members being connected by the transverse sections 13, 14

and 18; a bracket 5 attached to and extending above said side sections; a closing member 10 fitting between said hook members and lying beneath the transverse sections 13 and 14 and provided with the thumb-piece 15, and a spring secured to said bracket and closing member and adapted to hold the latter in engagement with said transverse sections, 40 whereby the trace-chain will be held in place, as specified and for the purpose set forth.

2. A trace-securing device for harness consisting of an anchoring or body section by which it is secured in place and further provided with parallel hook members having an open space between them and connected together at their ends by the transverse section 13 having an inwardly-directed rib 12; a bracket secured to the anchoring-section and extending above the same; a bifurcated spring secured to said bracket and carrying a closing member which is adapted to lie between the parallel hook-sections and is provided with a recess adapted to receive said 55 rib, whereby said member will be held against longitudinal movement, as specified and for the purpose set forth.

In testimony whereof I affix my signature in presence of two witnesses.

ALLEN R. DAYMON.
